by

PETER BROOKES

Inventor:

UNITED STATES PATENT OFFICE.

PETER BROOKES, OF KEARNEY, NEW JERSEY, ASSIGNOR TO NAIRN LINOLEUM COMPANY, OF KEARNEY, NEW JERSEY, A CORPORATION OF NEW JERSEY.

PLUNGER FOR CUTTING-CYLINDERS.

1,245,668.

Specification of Letters Patent.

Patented Nov. 6, 1917.

Application filed April 7, 1917. Serial No. 160,443.

To all whom it may concern:

Be it known that I, PETER BROOKES, a citizen of the United States of America, and residing at Kearney, in the county of Hudson and State of New Jersey, have invented a certain new and useful Improvement in Plungers for Cutting-Cylinders, of which the following is a specification.

My invention relates to plungers for cutting cylinders, and particularly for cutting cylinders of the type used in the manufacture of mosaic floor cloth, the object of my invention being to provide a plunger of improved construction which is not only more economically manufactured but also more expeditiously manipulated during the cleaning or repairing of the cylinder after use.

Referring to the accompanying drawings, Figure 1 is a partial section through a cutting cylinder in which plungers embodying my invention are mounted;

Fig. 2 is a side elevation of a plunger device detached from the cylinder;

Fig. 3 is a section therethrough; and

Fig. 4 is a dropped perspective of the plunger spindle and cap plate detached.

The apparatus to which my invention particularly pertains is the cutting cylinder of a machine for making inlaid linoleum of the general type illustrated in the patent to Walton No. 626,117. This cutting roll consists of a cylinder 10 the shell of which is pierced by numerous perforations 11 through which the plunger stems 12 pass into the interior of the cylinder. Within the latter is arranged the pattern roll 13, the surface of which is provided with a series of recesses 14, conforming to the pattern and into which the plunger stems 12 enter to permit the pattern tesserae to be retained by the cutting cylinder, whereas the plungers bearing upon the surface of the pattern roll are forced outward by the latter and throw out the material between the tesserae which it is desired to retain for the given pattern. In these particulars the apparatus is of well-known construction.

At its outer end each plunger 12 carries a head 15 which may conform generally to the shape of the tesserae cut by the knives 16 but having sufficient clearance to work freely in the space outlined by the knives. After the machine has been in operation some time, the sides of the knives and the head 15 of the plunger become gummed by

the material upon which they operate and it is necessary to clean them in order to assure the proper function of the apparatus. This cleaning operation is, at best, a tedious and time consuming matter. It has heretofore involved the removal of a retaining screw for each plunger head and the withdrawal of the latter after it has been freed, so that the knives and head may be properly cleaned. The operation is not only slow but it also involves the danger of the screw being insecurely replaced, with the attendant possibility of the head becoming detached from the plunger and fouling the knives, or in some other way damaging or interfering with the proper operation of the apparatus.

The present invention affords an improved plunger construction which facilitates the cleaning operation as well as rendering the manufacture of the plunger itself more economical than has heretofore been the case. Each plunger 12 is carried by a bushing 17 which is driven into one of the perforations 11 in the cylinder shell 80 and is wedged therein. An internal shoulder 18 is formed within the bore of the bushing in any suitable way, for instance, by means of a screw plug 19 threading into the tapped outer end of the bushing and provided with a central hole 20 through which the plunger passes. A collar 21 is formed on or secured to the plunger, and works within the inner end of the bushing. Between the shoulder 18 and the collar 21 is confined a light coil spring 22 which serves to retract the plunger after it has been pushed out by the pattern roll to extrude the material retained between the cutting knives. At its outer end the plunger 12 is bored or otherwise hollowed at 23 to receive the stem 24 of the plunger head 15. This stem is split at its inner end 25 and the split end slightly spread to afford a friction grip within the bore 23 of the plunger. The stem 24 may be integral with the head 15, or be secured thereto in any desired fashion. A hole 26 is formed in the plunger head and tapped to receive a threaded wire with handle loop, by which the operator may withdraw the head 15, with its split stem 24, from the hollow plunger 12, when it is desired to clean the knives and the plunger head. The reassembling of the plunger head and plunger is expeditiously accomplished

by merely pushing the split end 25 of the stem into the bore 23 in the outer end of the plunger.

The cleaning operation is thus greatly expedited. Moreover, the present construction eliminates the cost of tapping the plunger to receive the usual screw for retaining the plunger head; also the cost of the screw. Furthermore, it eliminates the necessity of forming a flange or pin in the plunger and its corresponding guide way in the bushing to prevent the rotation of the plunger in the latter when the usual securing screw for the head is screwed in. And this elimination of the pin and slot engagement between the plunger and bushing eliminates a possible danger to the proper functioning of the plunger and insures more perfect operation of the latter.

Modifications in detail will readily occur to those skilled in the art without departing from what I claim is my invention.

I claim:—

1. For use in a cutting cylinder of the type described a plunger having an inde-

pendent head and a stem rigid therewith, and means for frictionally engaging the stem with the plunger.

2. In a construction such as specified in claim 1, in which the plunger has an end bore and the stem is slotted to afford a frictional grip within said bore.

3. For use in a cutting cylinder of the type described, a bushing adapted to be secured in the cylinder shell, a plunger radially slidable in said bushing and a head for said plunger, said head having a stem engaging said plunger with a readily detachable connection.

4. For use in a cutting cylinder of the type described, a bushing adapted to be secured in the cylinder shell, a plunger radially slidable in said bushing and a head for said plunger, said head having a stem engaged with and disengaged from said plunger by a substantially straight push or pull, for the purpose described.

In testimony whereof I have signed my name to this specification.

PETER BROOKES.
